UNITED STATES PATENT OFFICE.

FREDERICK R. KEITH, OF RANDOLPH, MASSACHUSETTS.

INSOLE.

1,272,966.

Specification of Letters Patent. Patented July 16, 1918.

Application filed April 11, 1918. Serial No. 227,965.

To all whom it may concern:

Be it known that I, FREDERICK R. KEITH, a citizen of the United States, residing at Randolph, county of Norfolk, State of Massachusetts, have invented an Improvement in Insoles, of which the following description, in connection with the accompanying drawing, is a specification, like characters on the drawing representing like parts.

- 10 This invention relates to insoles of that type in which the inseam-receiving rib is formed from a strip or tape that is sewed to the body member adjacent the edge thereof, and the object of the invention is to provide 15 a novel insole of this type which can be expeditiously and inexpensively manufactured and which has various other advantages, all as will be more fully hereinafter set forth.
- 20 In order to give an understanding of my invention, I have illustrated in the drawings a selected embodiment thereof which will now be described, after which the novel features will be pointed out in the appended 25 claim.

Figure 1 is a perspective view of an insole embodying my invention;

Fig. 2 is an enlarged sectional perspective view of said insole;

- 30 Fig. 3 shows the strip or tape from which the inseam-receiving rib is formed.

Fig. 4 shows the strip or tape folded.

As stated above, my present invention relates to that type of insole in which the inseam-receiving rib is formed from a strip or tape of fabric sewed to the body member. Insoles of this type have the advantage that the body member can be formed of relatively inexpensive material. In an insole constructed for use in welt boots or shoes, it is important that the inseam-receiving rib should have sufficient strength to hold the inseam stitches because the strength and lasting qualities of the shoe depend largely on the strength with which the upper and welt are sewed to the insole. The body of the insole, however, is subjected to relatively little strain and hence can be made of inexpensive material, provided the inseam-receiving rib can be made with proper strength. The use of the tape of textile fabric for the inseam-receiving rib provides the necessary strength, regardless of the character of the body of the insole, and hence 55 an insole of this type can be made from inexpensive material.

In order to make a satisfactory insole of this type, it is important that the tape should be sewed at the proper distance from the marginal edge of the body, for if the tape is attached to the body at irregular distances, the inseam-receiving rib will be distorted. It is also desirable that the sewing or attaching of the strip to the marginal portion of the insole should not give undue thickness to such marginal portion. My improved invention accomplishes both of these objects, and thus produces a superior insole.

The body of the insole is indicated at 1 and may be made of any suitable material, 70 but will preferably be made of some relatively-inexpensive material, such as leather-board, thin leather, etc. The inseam-receiving rib is formed from a tape-like strip 2 of textile fabric, preferably duck fabric, which 75 is sewed to the body 1 near the marginal portion thereof. This strip is indicated at 3 and it is provided on one side with a coating 4 of adhesive material. The tape or strip is then folded longitudinally with the 80 coated side on the interior of the folded strip. The coating 4 thus causes the two plies of the folded strip to adhere together. The folded strip is sewed to the marginal portion of the body 1 by stitches 5 which 85 pass through the strip adjacent the edges 6 so that the folded edge stands upwardly from the body 1 thereby to form the inseam-receiving rib, as indicated in Fig. 2.

In order to make a proper insole, it is important that the folded tape or strip 3 should be sewed to the marginal portion of the body 1 at the proper distance from the edge thereof, and in order to form a positioning guide for said folded strip as it is 90 being sewed, I propose to channel the body 1 at its peripheral edge, and then to turn up the lip 7 therefrom. This channel will be cut at the desired depth at all points around the insole so that when the lip 7 is turned up 95 it will constitute a positioning rib or lip against which the folded strip 2 may be placed. Since this rib or strip is at the proper distance from the edge of the body portion at all points thereof, the folded strip 2 will be properly positioned at all points 100 around the insole if it rests against the upturned lip 7. Hence in attaching the folded strip or tape to the insole it is only necessary to use the upturned lip 7 as a positioning guide for positioning said tape or strip 105 as it is sewed to the insole.

In sewing the strip to the body 1 the plies or layers of the strip where the stitches 5 extend therethrough increase the thickness of the marginal portion of the insole, but 5 with the construction herein shown wherein the marginal portion 8 is reduced in thickness by the channeling operation and the turning up of the lip 7, the total thickness which results from the combined thickness 10 of the feather edge 8 and the two plies of the folded strip does not produce an undue thickness to the insole. The channeling of the insole and turning up of the lip, therefore, accomplishes two objects. In the first 15 place, it provides a positioning lip or rib for assisting in properly positioning the folded strip 2, and in the second place, it provides a reduced thickness to the feather edge 8 so that when the folded strip 2 is sewed thereto the combined thickness of the feather edge and folded strip will not produce an unduly thick insole.

There is also a decided advantage in making the inseam-receiving rib from a strip in

which the folded edge constitutes the top 25 edge of the rib because this folded edge will hold the inseam stitches much more firmly than a raw edge of fabric would. Further, the provision of the positioning lip 7 facilitates the sewing of the folded strip to the 30 body because it acts as a guide for the strip during the sewing operation so that the operator can rapidly sew the strips to the insole bodies with the certainty that the folded strips will always be properly positioned 35 relative to the edge of the insole.

I claim:

An insole comprising a body portion provided near its marginal edge with an upturned positioning lip and a folded tape encircling said lip and positioned thereby, said tape being sewed to the body portion exterior to the lip, that part of the body portion which is exterior to the lip being thinner than the central part of said body portion. 40 45

In testimony whereof, I have signed my name to this specification.

FREDERICK R. KEITH.
